UNITED STATES PATENT OFFICE.

ROBERT A. KINKELE AND CHARLES L. WOLFF, OF STAPLETON, NEW YORK.

FIREPROOF FLOOR.

SPECIFICATION forming part of Letters Patent No. 566,190, dated August 18, 1896.

Application filed May 6, 1896. Serial No. 590,436. (No model.)

To all whom it may concern:

Be it known that we, ROBERT A. KINKELE and CHARLES L. WOLFF, citizens of the United States, residing at Stapleton, in the 5 county of Richmond and State of New York, have invented certain new and useful Improvements in Fireproof Floors, of which the following is a specification.

This invention relates to a fireproof floor, especially that of the flat-arched type, and the object of the same is to furnish a substantial and durable and yet a comparatively light floor; and the invention consists of a fireproof floor comprising a series of supporting-blocks or tiles of inverted-T shape in cross-section, the side edges of the bases of said blocks being arranged so as to abut, while the central webs of said blocks provide spaces which are filled in with filling-blocks or tiles of suitable cross-section, as hereinafter set forth.

In the accompanying drawings, Figure 1 is a transverse section of a fireproof floor constructed in accordance with our invention. 25 Fig. 2 is a modified form thereof, also in transverse section. Fig. 3 is another modified form in transverse section. Fig. 4 is an isometrical view showing portions of two I-beams and a view of the blocks supported between the same, while the dotted lines show the ends of the blocks.

Similar letters of reference indicate corresponding parts.

The members of our improved fireproof floor are preferably supported on the flanges *a* of the usual I-beams or angle-irons *A*. The floor consists, in the main, of a number of blocks or tiles *B*, which are of inverted-T shape in cross-section and the bases *b* of 35 which abut. The upwardly-extending webs *b'*, formed by the stems of the T's, provide between them suitable spaces, which may be filled in with ashes, concrete, or any other suitable material, as shown in Fig. 4, or the 40 spaces may receive filling-blocks *C*, as shown in Fig. 1, said filling-blocks containing, as shown in said figure, either a number of bores or holes or a large chamber. The construction shown in Fig. 4 is for a cheaper 45 class of work, while that shown in Fig. 1 is for a more substantial and durable floor.

In Fig. 2 the spaces between the webs *b'* of the T-shaped supporting-blocks receive filling-blocks *C'* which are of T shape in cross-section and the edges of the top portions of 55 which are beveled or inclined, so as to fit corresponding bevels formed at the upper edges of the webs of the supporting-blocks, whereby an accurate and nice fit of the filling-blocks in the spaces between the webs of the supporting-blocks is obtained and the filling-blocks thereby firmly held in position without danger of displacement.

In Fig. 3 the webs *b'* of the supporting-blocks are shown as beveled at opposite sides 65 of their upper edges, as in Fig. 2; but the spaces between the webs receive slabs *C''*, the edges of which are beveled off, so as to correspond with the bevels of the webs.

In putting in a fireproof floor in accordance with our invention it is first necessary to place the supporting-blocks between the I-beams *A*, they being lowered by the workmen between the same and then turned transversely to such an extent that the end recesses 70 *b*², which are formed in the ends of the supporting-blocks, will receive the flanges *a* of the I-beams. The length of the supporting-blocks with reference to the spaces between the I-beams is such that when they are 75 placed in position they will be arranged at a slight obtuse angle, as shown clearly in the isometrical view, Fig. 4.

The principle of the invention is the same in all of the forms shown, and it is evident 85 that a builder may have his choice as to whether he desires a more costly or less costly construction, all of the constructions being quite durable and containing the gist 90 of the invention, which lies in a series of supporting-blocks of inverted-T shape in cross-section, and the side edges of the bases of which, that are formed by the flanges of the T's, abut, so that filling-blocks or tiles of 95 suitable cross-section can be arranged in the spaces between the webs of the supporting-blocks. The under surfaces of the bases of the supporting-blocks may furnish the ceiling, or plastering material may be applied thereto, so as to impart a finish, the flooring 100 being laid in the usual manner upon the upper part of the fireproof floor.

Having thus described our invention, we claim as new and desire to secure by Letters Patent—

1. A fireproof floor, consisting of a series 5 of supporting blocks or tiles of inverted-T shape in cross-section and arranged edge to edge at their bases, and filling blocks or tiles of suitable cross-section arranged in the spaces between the webs of the supporting-blocks, substantially as set forth.
2. A fireproof floor, consisting of a series of supporting blocks or tiles of inverted-T shape in cross-section and arranged edge to edge at their bases, and filling-blocks ar- 10 15 20

ranged in the spaces between the webs of the supporting-blocks and being of T shape in cross-section, the lower edges of the webs of said filling-blocks resting upon the abutting edges of the supporting-blocks, substantially as set forth.

In testimony that we claim the foregoing as our invention we have signed our names in presence of two subscribing witnesses.

ROBT. A. KINKELE.
CHAS. L. WOLFF.
